(57) **CLAIM**

The ornamental design for a shoe midsole periphery, as shown and described.

DESCRIPTION

FIG. 1 is a perspective view of a first embodiment of a shoe midsole periphery in accordance with my new design. FIG. 2 is a right side view of the embodiment of FIG. 1; FIG. 3 is a left side view of the embodiment of FIG. 1; FIG. 4 is a front view of the embodiment of FIG. 1; FIG. 5 is a rear view of the embodiment of FIG. 1; FIG. 6 is a top view of the embodiment of FIG. 1; FIG. 7 is a bottom view of the embodiment of FIG. 1; FIG. 8 is a perspective view of an second embodiment of a shoe midsole periphery in accordance with my new design. FIG. 9 is a right side view of the embodiment of FIG. 8; FIG. 10 is a left side view of the embodiment of FIG. 8; FIG. 11 is a front view of the embodiment of FIG. 8; FIG. 12 is a rear view of the embodiment of FIG. 8; FIG. 13 is a top view of the embodiment of FIG. 8; and, FIG. 14 is a bottom view of the embodiment of FIG. 8. Broken lines showing the remainder of the shoe in the figures are for illustrative purposes only and form no part of the claimed invention. The claimed stippled surfaces indicates contrasting surfaces of any texture, material, or color from the claimed surfaces devoid of stippling.
